UNITED STATES PATENT OFFICE.

WILLIAM H. MURPHY, OF INDEPENDENCE, MISSOURI, ASSIGNOR TO IRVING-PITT
MANUFACTURING COMPANY, OF KANSAS CITY, MISSOURI, A CORPORATION OF
MISSOURI.

LOOSE-LEAF HOLDER.

1,201,750.

Specification of Letters Patent. Patented Oct. 17, 1916.

Application filed September 24, 1913. Serial No. 791,470.

To all whom it may concern:

Be it known that I, WILLIAM H. MURPHY, a citizen of the United States, residing at Independence, in the county of Jackson and 5 State of Missouri, have invented a certain new and useful Improvement in Loose-Leaf Holders, of which the following is a specification.

My invention relates to improvements in 10 loose leaf holders.

The object of my invention is to provide a loose leaf holder adapted for ledger purposes, which is simple in construction, economical to manufacture, not liable to get out 15 of order, and which may be quickly opened and closed.

The novel features of my invention are hereinafter fully described and claimed.

In the accompanying drawings which 20 illustrate a preferred embodiment of my invention Figure 1 is a plan view showing the leaf supporting members in the extended or open position. Fig. 2 is a plan view, partly broken away, showing the leaf supporting 25 members in the collapsed or closed position.

Fig. 3 is a vertical section, on the line *a*—*b* of Fig. 2. Fig. 4 is a plan view of the oscillatable members and parts connected therewith, the nut being shown in horizontal section. Fig. 5 is a cross section on the line 30 *e*—*f* of Fig. 1. Fig. 6 is a cross section, on the line *c*—*d* of Fig. 1.

Similar reference characters designate similar parts in the different views.

1 and 2 designate respectively the leaf 35 supporting members, preferably consisting of right angled metal plates, having secured to them transverse leaf supporting pins 3, which are telescopically slidable in leaf sup- 40 porting tubes 4, of opposite members. The leaf supporting members 1 and 2, are slidably mounted toward and from each other, on a back member 5, which, as shown in Fig. 5, is preferably curved so as to have the 45 form of the back of a book.

Secured to the inner side of the back member 5, are housings forming bearings 6 and 7, between which and inwardly turned ends 8, of the back member, are guided and slidably mounted the leaf supporting members 1 and 2. Rotatively mounted in the housing 7, is a longitudinal screw 9, the outer end 50 of which is squared to receive an operating key, not shown, said outer end of said screw

being disposed opposite to a key hole 10, in 55 the adjacent end of the back member 5.

Mounted on the screw 9, within the housing 7, and movable inwardly and outwardly by said screw, is a nut 11, to which is secured one end of a longitudinally movable 60 connecting bar 12, which is pivoted by two pins 13 and 14 respectively, to two oscillatable members 15 and 16, preferably comprising flat horizontal disks, which are respectively pivotally mounted on axial pins 17 65 and 18 which are respectively secured, as shown in Fig. 3, to two brackets 19 and 20, which are secured, preferably by spot welding, to the inner side of the back member 5. For securing the bar 12 to the nut 11, said 70 bar is preferably provided in one edge with a notch 12' in which the nut 11 is fitted, Fig. 4, the bar at the same edge having a lateral tongue 11' which is fitted in a transverse slot 9' in the outer end of the nut 11. 75

Means are provided for simultaneously moving the leaf supporting members 1 and 2, in opposite directions, when the oscillatable members 15 and 16, are turned on their axes. Such means comprises preferably, two sets 80 of links. One set of links comprises two links, 21 and 22, which are pivoted to the leaf supporting member 1, and which are respectively pivoted by pins 23 and 24, to the oscillatable members 15 and 16. The other set 85 of links comprises two links 25 and 26, which are pivoted to the leaf supporting member 2, and which are respectively pivoted by pins 27 and 28, to the oscillatable members, 15 and 16. The pins 27 and 28, are located diamet- 90 rically opposite from the pins 23 and 24, and at equal distances from the axes of the oscillatable members 15 and 16. The connecting member 12, as shown in Fig. 4, is provided with an oblong slot 29, through which the 95 pin 14 extends.

To move apart the leaf supporting members, an operating key, not shown, is applied to the squared outer end of the screw 9, and turned in the proper direction, thereby moving the nut 11, from the position shown in Fig. 2, to the position shown in Fig. 1, thereby forcing the connecting bar 12, inwardly, thus moving the oscillatable members 15 and 16, in a counter-clockwise direction, to the 100 position shown in Fig. 1, at which time the links 21, 22, and 25 and 26, will have forced the leaf supporting members, 1 and 2, to the 105

open position shown in Fig. 1. To close the leaf supporting members the operating key is turned in the opposite direction from the direction in which it was turned to open said members. The leaf supporting members 1 and 2, may be supplied with the usual swinging covers, not shown.

I do not limit my invention to the structure illustrated and described, as modifications, within the scope of the appended claims, may be made without departing from the spirit of my invention.

Having thus described my invention, what I claim and desire to secure by Letters Patent is:—

1. In a loose leaf holder, a back member having inwardly turned ends and provided on its inner side with bearing means which include a housing, two leaf supporting members 20 slidably mounted between and guided by said bearing means and said inwardly turned ends, a screw rotatably mounted in said housing and held thereby from longitudinal movement, a nut fitted on said screw 25 and movable longitudinally thereby in and covered by said housing, and means actuated by said nut for moving the leaf supporting members toward and from each other.

2. In a loose leaf holder, a back member, 30 two leaf supporting members movable on said back member toward and from each other, a screw rotatably mounted on said back member and held thereby from longitudinal movement, a nut fitted on said screw 35 and movable lengthwise thereof and provided with a transverse slot, an operating bar fitted in said slot and provided with a recess in which said nut is fitted, and means actuated by said operating bar for simultaneously moving said leaf supporting members.

3. In a loose leaf holder, a back member provided on its inner side with an inverted U-shaped housing, two leaf supporting members 45 slidably mounted on the housing, an actuating member rotatably mounted in the two arms of the housing, and means actuated by the actuating member for moving the leaf supporting members toward and 50 from each other.

4. In a loose leaf holder, a back member

provided on its inner side with an inverted U-shaped housing, two leaf supporting members slidably mounted on the housing, a screw rotatably mounted in the arms of said housing, a nut mounted on the screw between said arms, and means actuated by the nut for moving the leaf supporting members toward and from each other.

5. In a loose leaf holder, a back member 60 provided on its inner side with two inverted U-shaped members, two leaf supporting members slidably mounted on said U-shaped members, the back member having on its inner side between said U-shaped 65 members a bracket, and means supported on said bracket and upon one of said U-shaped members for moving the leaf supporting members toward and from each other.

6. In a loose leaf holder, a back member 70 provided on its inner side with two U-shaped members and provided on its inner side between said U-shaped members with a bracket, two leaf supporting members 75 slidably mounted on said U-shaped members, an actuating member rotatably mounted in the arms of one of said U-shaped members, means supported by said bracket for moving the leaf supporting members toward and from each other, and means operated by said 80 actuating member for actuating said operating means.

7. In a loose leaf holder, a back member provided on its inner side with two U-shaped supporting members and a bracket 85 intermediate of said U-shaped members, two leaf supporting members slidably mounted on said U-shaped members, means mounted on said bracket for moving said leaf supporting members toward and from each 90 other, a screw rotatably mounted in the arms of one of said U-shaped members, a nut mounted on said screw, and means actuated by said nut for actuating said moving means.

In testimony whereof I have signed my name to this specification in presence of two subscribing witnesses.

WILLIAM H. MURPHY.
